UNITED STATES PATENT OFFICE.

HERMAN C. PRIEBE, OF BLUE ISLAND, ILLINOIS.

DRAFT-GEAR.

1,302,705.

Specification of Letters Patent.

Patented May 6, 1919.

Application filed December 3, 1917. Serial No. 205,211.

To all whom it may concern:

Be it known that I, HERMAN C. PRIEBE, citizen of the United States, residing at Blue Island, in the county of Cook and State of Illinois, have invented a certain new and useful Improvement in Draft-Gears, of which the following is a full, clear, concise, and exact description.

My invention relates to car structures and is of particular service in connection with those car structures which employ center or draft sills in the under frames thereof.

The invention has for one of its objects the provision of a construction whereby cheek plates or castings provided upon the draft sills are in supporting relation to the yokes of couplers throughout the ranges of movement of such yokes to relieve or lessen coupler supporting keys of undue strain and to secure other advantages.

The invention also has for its object the provision of an improved formation of coupler yokes. In carrying out this object of my invention I make the sides of the coupler yokes of U-shaped straps and in the formation of these straps elongated openings are provided into which cheek plates or castings extend to be in supporting relation to the coupler yokes throughout their normal ranges of movement.

All features of my invention will be more fully explained by reference to the accompanying drawings showing the preferred embodiment thereof and in which Figure 1 is a view in plan, partially in section on line 1—1 of Fig. 3; Fig. 2 is a view on line 2—2 of Fig. 1; Fig. 3 is a view on line 3—3 of Fig. 1; Fig. 4 is a perspective view of the preferred form of coupler yoke structure with the sides of the coupler yoke shown in partially separated relation; Fig. 5 illustrates an inner follower; and Fig. 6 illustrates a modified form of coupler yoke in which the U-shaped side straps that form the coupler yoke are made in one integral structure.

Like parts are indicated by similar characters of reference throughout the different figures.

In the form of the invention illustrated there is employed a coupler whose stem 1 has connected therewith a coupler yoke 2. The coupler butt 3 engages the outer follower 4 and the inner end of the coupler yoke engages the inner follower 5. The followers 4 and 5 are provided on their op-

posing faces with tubular extensions 6 and 7 that project toward each other. The motion resisting springs 8 and 9 surround the tubular extensions 6 and 7.

60

The draft gear structure thus far described is interposed between the center or draft sills 10. Where such draft gear is supplemented by motion resisting spring mechanism upon the exterior of the center or draft sills, motion to such exterior spring mechanism may be conveyed by continuations 11, 12 of the followers 4 and 5, these continuations being, for the sake of convenience in construction and assembly, in the form of keys which pass through the followers as indicated clearly in Figs. 1 and 2. In order that the springs may be properly associated with the ends of the key continuations 11 and 12 of the followers 4 and 5, the ends 75 of these key extensions are passed through slots in the follower blocks 14 between which the springs 15, 16 are interposed, these follower blocks being maintained in assembly with the keys by means of cotter pins 17, 18. 80 The followers 13 and 14 are provided on their opposing faces with tubular extensions 19, 20 which project toward each other and are in telescoping relation. The motion resisting springs 15 and 16 surround the tubular extensions 19 and 20.

A key 21 passes through the coupler stem and moves longitudinally of the car structure therewith. This key is prevented from endwise displacement by means of cotter pins 22 that are upon the exteriors of the center sills 10. Cheek plates or castings 23 are secured upon the inner faces of the center sills. These cheek plates are provided with elongated slots 24 that register with corresponding slots 25 in the center sills and in which slots the key 21 is movable longitudinally of the center sills. The cheek plate is provided with elongated slots 26 that register with corresponding slots 27 in the center sills and in which slots the key 21 is movable longitudinally of the center sills. 90 The cheek plates are provided with elongated slots 28 that register with corresponding slots 29 in the center sills and in which slots the key 21 is movable longitudinally of the center sills. The outer ends of the slots 26, 27 define the limit to which the key 21 may be outwardly moved and the inner ends of these slots define the limit 95 to which the key 21 may be inwardly moved. The outer ends of the slots 28, 29 define the

limit to which the key 12 may be outwardly moved and the inner ends of these slots define the limit to which the key 12 may be inwardly moved. The yoke has elongated 5 horizontal openings 21 in which the cheek plates or castings 23 project, a relation which is maintained owing to the fact that the followers 4, 5 are of sufficient width practically to span the gap between the 10 cheek castings to prevent the yoke from being moved laterally to such an extent as to become disengaged from one or the other of the cheek castings. By this arrangement the yoke is supported directly upon the 15 cheek castings in the event of breakage or removal of the keys 11 and 12 and the load of the yoke and the parts of the draft gear carried by the yoke is borne in part by the cheek castings and not wholly by the keys 20 whereby these keys are relieved of shearing and other strains to an appreciable extent.

The yoke is, under normal conditions, supported throughout its range of movement at all times upon the cheek plates or 25 castings whereby the keys are, under normal conditions, relieved as set forth. The horizontal openings 21 are continued outwardly so as to also receive the coupler key 21 as well as the keys 11 and 12. 30 The elongated horizontal openings 21 are produced by making the coupler yoke of bar iron or steel which may be forged or cast. The preferred form of coupler yoke is illustrated most clearly in Fig. 4 and 35 includes two separate side straps each of U-shape with the sides of each U in an upright plane. The base of each U is at the outer end of the draft rigging. The inner ends of each U are extended crosswise toward the other U to form hooks 30 whose 40 short ends extend lengthwise of the yoke and outwardly with respect to the draft gear. The yoke of the coupler is formed of two side straps of bar iron each of U- 45 shape, each U-shaped strap having its sides spaced clear from the inner end thereof to its base, the ends of the U-shaped straps opposite the bases thereof extending crosswise. The inner follower 5 has formed 50 therein, at its inner end, pockets 51 that receive the short ends of the hooks 30 and prevent them from straightening. In the preferred embodiment of the invention the short ends of the hooks 30 upon each side 55 strap of the yoke are maintained, by the pockets 51, in engagement with the short ends of the hooks 30 upon the other side strap of the yoke whereby these engaging short ends of the hooks coöperate with the

pockets 51 to prevent these short ends from 60 straightening. In Fig. 4, for the sake of clearness, the side straps of the hook are shown as being slightly separated but they are preferably more closely approached in order that the short ends of the hooks 30 65 may be engaged as just described. In the form shown in Fig. 6 the side straps of the yoke are made in one integral bar with the upper hooks 30 merged with each other and the lower hooks 30 merged with each other, 70 but I prefer to employ the form shown in Fig. 4 where the straps are separately made.

While I have herein shown and particularly described the preferred embodiment of my invention I do not wish to be limited to the precise details of construction shown as changes may readily be made without departing from the spirit of my invention, but having thus described my invention I claim as new and desire to secure by Letters 75 80 Patent the following:—

1. Draft gear including a coupler having a coupler yoke formed with two separate side straps of bar iron each of U-shape with the bases of the U-shaped straps outermost 85 and the inner ends of each U-shaped strap extending toward the other strap and forming hooks with short ends, each U-shaped strap having its sides spaced apart for the reception of inner and outer follower elements therebetween; an outer follower having a portion located between the sides of the U-shaped straps at the outer ends of the yoke; and an inner follower having a portion located between the sides of the U- 95 shaped straps and engaged by the inner ends of the straps, said inner follower having pockets that receive said short hook ends.

2. Draft gear including a coupler having 100 a coupler yoke formed with two side straps of bar iron each of U-shape with the bases of the U-shaped straps outermost and the inner ends of each U-shaped strap extending toward the other strap, each U-shaped 105 strap having its sides spaced apart for the reception of inner and outer follower elements therebetween; an outer follower having a portion located between the sides of the U-shaped straps at the outer ends of the 110 yoke; and an inner follower having a portion located between the sides of the U-shaped straps and engaged by the inner ends of the straps.

In witness whereof, I hereunto subscribe, 115 my name this first day of December, A. D. 1917.

HERMAN C. PRIEBE.
